J. J. REICHERTS, OF DELAWARE, OHIO.

Letters Patent No. 85,852, dated January 12, 1869.

IMPROVEMENT IN FENCES.

The Schedule referred to in these Letters Patent and making part of the same.

To all whom it may concern:

Be it known that J. J. REICHERTS, of Delaware, in the county of Delaware, and State of Ohio, have invented a new and useful Improvement in Fences; and I do hereby declare that the following is a full, clear, and exact description thereof, which will enable those skilled in the art to make and use the same, reference being had to the accompanying drawings, forming part of this specification.

This invention relates to a new and useful improvement in fences for door-yards, and for all other purposes to which the same may be applicable; and

It consists in attaching wire pickets to the rails of the fence, in the manner hereinafter described.

The drawing represents a longitudinal section of a fence constructed according to my invention.

This fence is built in sections, with either wood, iron, or stone posts, and with either wood or iron rails, of any suitable size.

The pickets are made of iron wire or rods of suitable diameter, formed with eyes for the top and for the bottom rails, so that they may be slipped on to the rails, as seen in the drawing.

A represents the posts;

B, the rails; and

C, the pickets.

As seen in the drawing, the pickets are double, with the parts spread asunder, with two eyes, *d d*, for the top rail, and two, *e e*, for the bottom rail, as seen in the picket marked C', which, in form and construction, represents all the others. There may be more than two

rails, and, consequently, more than four eyes in each picket. These eyes are formed by giving the wire or rod a single turn.

The picket is made of a single rod or piece of wire, so bent that the legs *f f* cross each other, as seen at *g*, with the ends of the rod extending down below the eyes *e*, as seen at *h*.

These legs *f f* not only cross each other, but each crosses the legs of the adjacent picket, as seen at *i i*, and so on throughout the section or paling, thus forming a lattice-work of diamond-shaped, or curved and other apertures, between the rails.

The upper parts of the pickets (which form a succession of Gothic arches) lap over each other, as seen at *j*.

The pickets, thus formed, (or formed otherwise, as regards their configuration, with the eyes *d d* and *e e* always preserved,) are slipped on to the rails, as represented in the drawing, thus forming a handsome and durable iron rail-and-picket fence, without any drilling, riveting, or welding, and at a very cheap rate.

I claim as new, and desire to secure by Letters Patent—

The picket C, with the eyes *d d* and *e e*, in combination with the rails B B, and posts A, or their equivalents, arranged on the rail so as to form a fence, substantially as shown and described.

J. J. REICHERTS.
